UNITED STATES PATENT OFFICE

FREDERICK LAGE, OF GLADBROOK, IOWA

ROAD AND FIELD CONDITIONING DEVICE

Application filed August 30, 1928. Serial No. 302,988.

The principal object of this invention is to provide a road and field conditioning device that successfully crushes and distributes the dirt, loam and the like over which it is drawn.

A further object of this invention is to provide a road and field conditioning device that is capable of furrowing the ground over which it passes.

10 A still further object of this invention is to provide a road and field conditioning device that is so constructed that when one of the earth engaging members is lifted by a rise in the ground or a comparatively large clod of earth the whole device is lifted, thereby causing approximately the entire weight of the complete device to rest upon the earth engaging member that has been raised.

20 A still further object of this invention is to provide a device for the conditioning of either roads or fields that may be easily converted from one use to the other by merely changing its direction of pull.

25 A still further object of this invention is to provide a road and field conditioning device that is economical in manufacture and durable in use.

These and other objects will be apparent to those skilled in the art.

30 My invention consists in the construction, arrangement and combination of the various parts of the device, whereby the objects contemplated are attained as hereinafter more fully set forth, pointed out in my claims and illustrated in the accompanying drawings, in which:

Fig. 1 is a top plan view of my complete invention ready for use as a clod crusher or soft earth leveler.

40 Fig. 2 is an end view of my invention more fully illustrating the position of the angle irons when the device is used as a clod crusher and soft earth leveler.

45 Fig. 3 is an end view of my device illustrating the position of the angle irons when the apparatus is used as a scraper for the conditioning of roads and the like.

50 Fig. 4 is a back elevation of the last angle iron of the invention, when the device is used as a clod crusher or soft earth leveler and

shows the teeth attached thereto for furrowing the earth.

Fig. 5 is an end view of the trailing angle iron, when the device is used as a clod crusher or soft earth leveler, showing the counter-balance weight for holding the angle iron in proper position so that the teeth attached thereto will more successfully furrow the ground over which the device passes.

The chief disadvantages of road and field conditioning machines now being sold to the general public are their failure to be readily converted from field use to road use and their inability to properly level and smooth the earth without undue packing. I have overcome these disadvantages as will be apparent to those skilled in the art.

I have used the numerals 10, 11 and 12 to designate spreader bars spaced apart, as shown in Fig. 1. Secured by suitable means such as spot welding and the like to the under side of each of these spreader bars are a plurality of half rings which I have designated by the numeral 13. Each of these rings is designed to pass through a hole 14 located near the marginal edge of the angle iron 15, as shown in the drawings. By this construction, it will be noted that all of the angle irons 15 will be spaced apart and hinged at one of their marginal edges to and in a transverse relation to the spreader bars 10, 11 and 12.

When the invention is to be used as a clod crusher or soft earth leveler, as illustrated in Fig. 2, the leading marginal edges of each of the angle irons except the forward angle iron will be hinged to the spreader bars and the trailing marginal edge of each of the angle irons except the rear angle iron will engage the under side of the spreader bars, thereby rigidly holding the lower corner of each of the angle irons in a downward position where they engage the earth and act as the earth engaging members of the device. It is unnecessary for the forward angle iron to be hinged to the spreader bars at its leading marginal edge due to the fact that, when the device is used for field purposes the pull on the device for dragging it over the earth will be exerted on the leading marginal edge.

of this angle iron by having the two tow rods 16 and 17 detachably entering and engaging the holes 18 and 19 respectively, in that angle iron and thereby holding it in proper position, as shown in the drawings. The forward ends of each of the tow rods 16 and 17 are secured to the tow ring 20 designed to be secured in the ordinary manner to a suitable power for dragging the device over the ground to be conditioned.

Secured by suitable means to the trailing side of the rear angle iron is a bar 21 having a plurality of teeth 22 extending in the same plane as the plane of the leading side of that angle iron and which is illustrated in Fig. 2.

The purpose of these teeth 22 is to furrow or crease the soft earth over which the device has passed, in order that it will not be susceptible to erosion by wind or water. As this rear angle iron does not engage the spreader bars at its trailing marginal edge, I have provided the counter-balance weights 23 detachably secured to the trailing upper marginal edge of that angle iron by suitable means, which yieldingly hold the teeth 22 in proper contact with the earth over which the device passes. By the above described arrangement of my invention it will readily be noted that, when any one of the earth engaging members encounters a rise in the ground or a comparatively large clod it will raise the spreader bar or spreader bars to which it is secured, which in turn will lift all of the angle irons, thereby bringing approximately the entire weight of the invention upon the rise in the ground or the clod and successfully level or crush the same.

By the leading sides of the angle irons extending at a downward and backward angle to the ground, there will be very little scraping action and the device may be pulled over the earth without undue resistance as the tendency of the earth will be to allow the invention to slide over it, thereby slightly packing, leveling and conditioning the same. As the angle irons are each hinged at one of their marginal edges to the spreader bars, a noticeable flexibility of the complete device is readily noticed and the device will experience no difficulty in conforming to the outline of the earth over which it passes.

When the invention is to be used as a road machine the two tow rods 16 and 17 are detached from the forward angle iron and secured to the rear angle iron by hooking into the holes 24 and 25, respectively, in that angle iron, as shown in Fig. 3, and reversing the direction of pull of the device. The counter-balance weights 23 should be removed as they are not necessary and are in the way when the device is to be used as a scraper. In fact, these weights are not necessary when the device is used as a field machine, if the earth is very soft. As soon as the device is pulled in the direction as shown in Fig. 3, the origi-

nal leading side of all of the angle irons except the trailing angle iron will engage the underside of the spreader bars 10, 11 and 12, thereby bringing the free marginal edge of the angle irons in a right angle to the earth over which the device passes. Such a construction is very rigid and makes a most excellent scraper for roads and may often be used to advantage in the field. The now trailing angle iron remains in a normal flexible condition with its outer corner engaging the ground over which the device passes, thereby leaving the earth in a smooth condition. If the road bed is very soft the device as a field machine may be used instead of the scraper arrangement.

It will readily be seen that I have provided an efficient road and field conditioning machine that may be quickly changed from the use of one to the other by merely reversing its direction of pull.

Some changes may be made in the construction and arrangement of my improved road and field conditioning device without departing from the real spirit and purpose of my invention and it is my intention to cover by my claims any modified forms of structure or use of mechanical equivalents which may be reasonably included within their scope.

I claim:

1. In a device of the class described, a plurality of spreader bars, a plurality of angle irons each having a plurality of holes, and curved members each secured to one of said spreader bars and passing through a hole in one of said angle irons.

2. In a device of the class described, a plurality of spreader bars, a plurality of angle irons hinged at one of their marginal edges to the underside of said bars, and teeth secured to the outer side of one of said angle irons and extending in a transverse relation thereto.

3. In a device of the class described, a plurality of spreader bars, a plurality of angle irons each having a plurality of holes near one of its marginal edges, and a plurality of curved members each secured to one of said spreader bars and passing through a hole in one of said angle irons.

4. In a device of the class described, a plurality of spreader bars, a plurality of angle irons each having a plurality of holes, and curved members each secured to the underside of one of said spreader bars and passing through a hole in one of said angle irons, respectively.

5. In a device of the class described, a plurality of spreader bars, a plurality of angle irons each having a plurality of holes, curved members each secured to one of said spreader bars and passing through a hole in one of said angle irons, and a counter balance weight on one of said angle irons.

6. In a device of the class described, a plu-

rality of spreader bars, and a plurality of angle irons each having one of its marginal edges hinged to the underside of said bars whereby its swinging movement in one direction will be limited by coming in contact with the underside of said bars.

FREDERICK LAGE.
